(57) **CLAIM**

The ornamental design for a wedge for door lock of automobile, as shown and described.

DESCRIPTION

FIG. 1 is a front perspective view of a wedge for door lock of automobile showing my new design;

FIG. 2 is a front view thereof;

FIG. 3 is a rear view thereof;

FIG. 4 is a top plan view thereof, the bottom plan view being a mirror image of FIG. 4;

FIG. 5 is a right side view thereof;

FIG. 6 is a left side view thereof; and,

FIG. 7 is a referential view showing the article in use.

The features shown in broken lines in the drawings depict environmental subject matter only and form no part of the claimed design.

1 Claim, 6 Drawing Sheets
